Harry Frease Attorney

UNITED STATES PATENT OFFICE

BARNETT GERSHOVITZ, OF CANTON, OHIO

FLOOR MOP

Application filed October 26, 1929. Serial No. 402,621.

The invention relates to floor mops and more particularly to a mop provided with a wringing device therefor; the present application being an improvement upon my Patent No. 1,632,470, dated June 14, 1927.

The object of the improvement is to simplify and improve mops of this general character.

An embodiment of the invention is illustrated in the accompanying drawing, in which

Figure 1 is a perspective view of the improved mop;

Fig. 2, a plan sectional view of the mop frame; and

Fig. 3, a section on the line 3—3, Fig. 2.

Similar numerals refer to similar parts throughout the drawing.

The handle 10 is provided, near its lower end, with the crank 11 pivoted therethrough and having the elongated loop 12 upon one end and the crank handle 13 upon the other end.

The mop frame is indicated generally at 14 and formed of a single heavy wire or rod bent upon itself at its middle portion as at 15 and having the oppositely disposed eyes or loops 16, both ends of the wire frame extending forward in parallel relation as at 17 and then preferably outward at an angle as at 18 and again forward in parallel relation as at 19, each having the U-shaped portion 20 terminating in the upwardly and inwardly disposed angular portion 21.

The fixed jaw 22 of the mop is preferably formed of sheet metal bent upon itself, providing a double thickness at 23 and having the transversely concave forward edge 24.

The U-shaped portions 20 of the frame are located between the folds 23 and fixed therein by any suitable and well known manner, as indicated at 25. The movable jaw 26 is formed of heavy wire or rod, having the straight portion 27 adapted to be received in the concave face 24 of the fixed jaw, the ends thereof being turned back as at 27^a and then curved toward each other as at 28, terminating in the spaced aligned straight portions 29.

A lever 30 is provided for operating the movable jaw. This lever may be formed of

sheet metal having the handle portion 31 and the angular legs 32, the end portion of each leg being pivoted to the corresponding in-turned end 21 of the frame, said ends of the frame being upset as at 33. The aligned ends 29 of the movable jaw are pivoted through intermediate portions of the legs 32 and upset as at 34.

A sheet metal plate 35 is attached to the intermediate reduced portion of the frame as by the lugs 36 and 37 and provided with the spaced upright ears 38 to which the lower end portion of the handle 10 may be pivotally connected as by the pin 39.

The mop cloth 40 is adapted to be attached to the handle by running the same through the loop 12, the ends of the mop cloth being passed over the straight portion 27 of the movable jaw. After the mop cloth has been thus attached, the mop is placed in the position shown in Fig. 1 and is ready for use.

Downward or forward pressure upon the handle 10 causes the frame to lie flat upon the floor, flattening the mop cloth and holding it to the floor during the mopping operation.

When it is desired to wring the mop, the handle may be raised to a substantially horizontal position, permitting the frame and jaws to hang downward therefrom and the crank handle 13 may then be turned, twisting the mop cloth and wringing the water from the same.

When it is desired to remove the mop cloth, it is only necessary to swing the lever 30 forward into the dotted line position shown in Fig. 3, moving the movable jaw 25 away from the fixed jaw, permitting the end of the mop cloth to be easily removed and a new cloth to be replaced and clamped therein by swinging the lever back to the normal position shown in full lines in all of the figures of the drawing.

I claim:

1. A mop including a handle, a frame pivotally carried by the handle, the frame comprising a portion formed of wire having forwardly extending spaced legs provided with in-turned ends, a fixed jaw carried by the forward portion of the legs, a lever pivoted to the in-turned ends of the legs, and a movable

jaw pivotally connected to the lever and cooperating with the fixed jaw for clamping a mop cloth therebetween.

2. A mop including a handle, a frame pivotally carried by the handle, the frame comprising a portion formed of wire having forwardly extending spaced legs provided with upturned and inturned ends, a fixed jaw carried by the forward portion of the legs, a lever pivoted to the inturned ends of the legs, and a movable jaw pivotally connected to the lever and cooperating with the fixed jaw for clamping a mop cloth therebetween.

In testimony that I claim the above, I have
hereunto subscribed my name.

BARNETT GERSHOVITZ.
